UNITED STATES PATENT OFFICE.

THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

POLISHING ELEMENT FOR RATTLING DEVICES.

1,133,368.

Specification of Letters Patent. Patented Mar. 30, 1915.

Application filed February 25, 1914. Serial No. 820,955.

To all whom it may concern:

Be it known that I, THOMAS A. DE VILBISS, a citizen of the United States, and a resident of Toledo, in the county of Lucas and State of Ohio, have invented a certain new and useful Polishing Element for Rattling Devices; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to tumbling or rattling devices of the class employed in connection with the cleaning or polishing of small articles, and has particular reference to the formation of the loose rattling or tumbling parts or elements which have polishing or cleaning contact with the articles. The invention is not restricted to such use, however, as it may be used in any connection for which it is adapted or appropriate.

The object of my invention is the provision of a rattling or tumbling element of the character described, which is other than of true spherical form, whereby it may adapt itself to the different curvatures, or to openings, recesses, or the like, of different sizes and shapes, and to irregularities in the articles being operated on, thus making the finishing of articles with rattling elements of this class more rapid and efficient than is possible with elements of the spherical type. Further objects and advantages of the invention will be apparent from the following detailed description.

The invention is fully described in the following specification, and while, in its broader aspect, it is capable of embodiment in numerous forms, a preferred embodiment thereof is illustrated in the accompanying drawings, in which,

Figure 1 is a side view of the preferred form of rattling element embodying my invention. Fig. 2 is a side elevation of a plurality of such elements arranged in circular form to illustrate that the outer sides of such elements when so arranged form arcs of a common circle. Figs. 3 and 4 are side views of different forms of elements from that shown in Fig. 1, and Figs. 5 and 6 are enlarged longitudinal and cross sec-

tions, respectively, of the element shown in Fig. 1, with such sections taken on the major and minor axes thereof.

In order to secure a rapid and efficient polishing or cleaning of articles by the tumbling or rattling process it has been found from experiments that the rattling elements preferably should be of curved elongated form to present broad contacting surfaces to the articles being operated on, and also to make one or both of the end portions of an element of more or less pointed form to enable such end or ends to project into openings or recesses of different sizes and to automatically adjust itself to the size of the opening, or in other words, to move a greater or less extent into the openings as the size of the opening or recess may permit.

The element shown in Fig. 1 and designated 10 is substantially circular in cross-section from one end to the other thereof, and has opposite sides forming arcs, which are struck from different axes, with such arcs preferably disposed without the element, or, in other words, a plurality of elements may be arranged end to end in circular form with their outer sides forming adjoining arcs of a circle and with their inner sides struck from points within the circle and being of the same radii as the outer arcs.

In Fig. 3 the rattling element, which is designated 11, is shown as being of elliptical form in longitudinal section, and in Fig. 4 the element, which is designated 12, is shown as being of egg-form, or, in other words, combining the features of both elements 10 and 11 having one end of pointed form and the other end curved in the form of the end of an ellipse.

It will be understood that the invention is not limited to articles of the forms shown, but that such forms are merely illustrative in their character and the element may be of numerous other forms having major and minor axes. By making at least one end of the rattling element of a form whereby the cross-sectional diameter thereof gradually increases inwardly from such end, the element is enabled to project a greater or less extent into an opening or recess depending upon the size of the opening or recess, thus adapting it to perform work which would be impossible with a rattling element of spherical form. It is preferable to taper or

gradually restrict an end portion of an element outwardly from or adjacent to its center of gravity.

It is found in practice that the use of rattling elements of the type substantially as shown in Fig. 1 will polish articles in a very much more efficient manner than elements of the spherical type and in from one-third to one-quarter the time, thus enabling work to 10 be turned out very much more rapidly by the use of rattling elements of the character shown than is possible with spherical rattling elements, and consequently effecting a material saving in the expense incident to 15 the polishing and cleaning of articles by the rattling or tumbling process.

In the use of the spherical type of rattling elements, it is necessary to change the size of the element to suit the work being acted 20 on or in other words the elements must be of sufficient size to prevent the complete passage thereof into openings in the article. With applicant's form of rattling element 25 one size may be used for work having numerous sized openings and the element

is at the same time adapted for entry or fitting into recesses and uneven surfaces to polish the same due to the oblong or pointed form thereof.

I wish it understood that my invention is 30 not limited to any specific form, construction or material, as numerous modifications may be made within the spirit of the invention.

Having thus described my invention, what 35 I claim as new, and desire to secure by Letters Patent, is,—

A metal polishing element of the class described which is elongated in form, circular in cross-section throughout its length 40 and terminating at each end in a point, said element having lengthwise extending side arcs intersecting at the ends thereof.

In testimony whereof, I have hereunto signed my name to this specification in the 45 presence of two subscribing witnesses.

THOMAS A. DE VILBISS.
